UNITED STATES PATENT OFFICE.

ALBERT H. CROCKER, OF CHICAGO, ILLINOIS.

ELECTRICAL IGNITION APPARATUS.

990,960.

Specification of Letters Patent.

Patented May 2, 1911.

Application filed January 3, 1910. Serial No. 536,063.

To all whom it may concern:

Be it known that I, ALBERT H. CROCKER, a citizen of the United States, and resident of Chicago, Cook county, State of Illinois, have invented certain new and useful Improvements in Electrical Ignition Apparatus, of which the following is a specification.

My invention relates to certain novel improvements in spark controllers for magneto equipped gas engines, and has for its object primarily the provision of a spark controller, by means of which the time of the spark may be advanced or retarded while the strength of the spark will always be maintained at a maximum.

In magneto equipped gas engines, the sparking system ordinarily employed consists of an armature with but one winding, and giving a current of comparatively low potential which is stepped up by a transformer to a voltage sufficiently high to jump the gap between the electrodes in the cylinders. The advance or retardation of the spark has been accomplished in various ways, but usually by changing or adjusting the circuit breaker mechanism, to break the circuit and produce the spark at any desired time relatively to the position of the cylinder pistons, without changing the driving connection between the crank-shaft and the magneto. It is well known that a magneto of this type will give a maximum spark, when in its revolution its winding is in a plane substantially at right angles to the field magnets. If the angular relation between the magneto shaft and the crank-shaft is a fixed one, it will be evident that the maximum spark can be obtained only at one position of the crank-shaft and piston. Any change of the time of sparking by adjusting the circuit breaker, will result in a diminution of the strength of the spark, for the reason that the armature will not be in a plane perpendicular to the field magnets at the time the circuit is broken, to produce the spark. I have overcome this objectionable feature in magneto equipped engines, by providing a mechanism by means of which the angular relation of the magneto armature to the crank-shaft can be changed so that the spark will always be delivered when the armature is in its position of maximum efficiency, and the timing of this maximum spark can be regulated to permit it

to be advanced or retarded with relation to the position of the pistons in the cylinder.

For the purpose of aiding in the description of my invention, I have illustrated a preferred embodiment thereof, in the accompanying drawings. To the exact structure disclosed, however, I do not wish to be understood as limiting myself, the true scope of my invention being set forth in the appended claims.

Referring to the drawings which disclose my preferred embodiment Figure 1 is an end elevation of a magneto equipped gas engine. Fig. 2 is an elevation partly in section through the center of the magneto and spark controller, shown in Fig. 1. Fig. 3 is an enlarged section of the spark controller taken on the line 3—3 of Fig. 2. Fig. 4 is a view looking toward the right in Fig. 3 and with the frame and sliding cam removed and part of the bearing ring being broken away. Figs. 5, 6, 7, and 8 are perspectives of the wedge-shaped cam and cap, the bearing ring, the driving gear, and the bearing disk, respectively. Figs. 9, 10, and 11 are perspectives of the operating cam and its frame, the set nut, and the end of the magneto shaft, respectively.

I have chosen to illustrate the preferred embodiment of my invention in connection with a type of gas engine such as is ordinarily used on motor cycles, and comprising, as shown in Fig. 1, two cylinders 5, operating a crank shaft 6, suitably mounted in a casing 7, but it will be clear from a better understanding of my invention, that it may be employed with any type of gas engine, its use not being limited to motor cycles. In the type of engine disclosed, the crank shaft 6 is connected to the driving gear 8 mounted on the magneto shaft 10, by a train of gears comprising idler wheels 9, and 11, which are so proportioned that a constant relation is maintained between the crank shaft and the driving gear. If the driving gear were immovably secured on the magneto shaft the angular relation of the magneto shaft and crank shaft would always remain constant and the armature would be brought into its plane of greatest efficiency each time the crank shaft, and consequently the pistons, arrived at a certain point in the cycle. I have therefore, loosely mounted the driving gear on the magneto shaft as will be hereinafter described.

110

In Fig. 2 is shown a common type of magneto consisting of the field magnets 12, and the armature 13, provided with the single winding 14. Upon one end of the magneto shaft is secured a transformer 15 which may be of any ordinary or preferred construction; and located above the magneto on the magneto frames is the distributor 16. It will be understood that when my invention is employed with two-cylinder gas engines, the distributor may be dispensed with; but as my invention is adapted to be used with engines of varying sizes and having a varying number of cylinders, I have chosen to illustrate a commercial form of magneto which is ordinarily supplied with a distributor, the one disclosed being for use in connection with a four-cylinder engine. The other end of the magneto shaft 10, is turned down to provide a tapering portion 17, upon which is adapted to fit, the hub 18 of the bearing disk 19, which disk is fixedly secured on the shaft by means of the set nut 21, which is slotted at its outer end and is adapted to be screwed upon the threaded end of the shaft. The bearing disk 19 is provided with an annular seat or bearing 22, as best shown in Fig. 3, which is adapted to receive and support the inner side of the annular driving gear 8. A bearing ring 23 is provided with a similar bearing 24 which is adapted to fit inside the annular gear 8, and together with the bearing 22 of the disk 19 to form a bearing sector which provides a seat upon which the annular gear 8 may be moved angularly relatively to the shaft 10. The bearing ring 23 and the disk 19 are secured together with the gear 8, between them, by rivets, bolts or other fastening means adapted to pass through the holes with which they are provided, as shown in Figs. 6 and 8. A portion of the bearing 24 on the bearing ring 23 is cut away as clearly shown in Fig. 6, for the reception of an inwardly projecting lug 25, on the interior of the annular gear 8.

The inner face of the disk 19 is provided with a block 26, as shown in Fig. 4, which is fastened to the inner face of the disk at one side of the opening 27 therein. This opening is adapted to receive the front end of a wedge-shaped cam 28, integral with a cap 29, which is adapted to slightly fit over the set-nut 21. The outer end of the cap 25 is provided with a lug 31 adapted to be engaged by a sliding cam 32, to force the wedge-shaped cam into the opening 27 in the disk 19, one face of the cam bearing against the block 26 and the other against the inwardly projecting lug 25, to force the lug 25 away from the block 26, thereby changing the angular relation of the driving gear to the magneto shaft. The sliding cam 32 is carried in a housing 33 adapted to be secured to the frame 34 of the machine.

The housing is provided with a beveled slot 35 as shown in Fig. 9, so that the sliding cam may be inserted into the housing by projecting its outer end 36 through a bearing opening 37 in the side of the housing. For the purpose of guiding the other end of the cam and maintaining it in its proper position in the housing relatively to the cap 29, I have provided the end of the cam with a projecting pin 38, which extends through and is adapted to be reciprocated in an opening in the housing opposite to the bearing opening 37. Longitudinal movement is imparted to the cam 32 by means of a rod 39, which, in the embodiment disclosed, is adapted to be connected with one of the grips of the motor cycle, not shown. This rod is connected at its lower end to the usual locking member 41 and the exhaust valve controlling device 42. A rod 43 completes the connection between the cam and the rod 39, by being secured at one end to said cam and at its other end to the locking device 41 as clearly shown in Fig. 1. When it is desired to slow down the engine, by retarding the spark the sliding cam 32 is forced upwardly looking at Fig. 3, by the connecting rods above described, thus partially withdrawing the wedge-shaped cam 28 from between the block 26 and the lug 25, permitting backward angular movement of the magneto shaft relatively to the driving gear without changing the relative relation of the magneto shaft to the circuit breaker. It will be evident that the change in angular relation between the armature shaft and the driving gear will retard the time of deliverance of the spark relatively to the position of the engine pistons. Since the relation between the armature shaft and the circuit breaker is not disturbed, the circuit will be broken and the spark produced when the armature winding is in its position of maximum efficiency relative to the field magnets. Thus, by changing the angular relation between the crank-shaft of the engine and the magneto shaft, without disturbing the relation between the circuit breaker and the magneto shaft, I am enabled to vary the time of deliverance of the spark without diminishing its strength and efficiency.

While I have illustrated and described a preferred embodiment of my invention, I am aware that it may be carried out in many other forms than that shown, without departing from the scope thereof, as expressed in the claims; therefore, I do not wish to be limited to details shown, but wish to claim all such modified forms as would come properly within the general scope of the invention.

What I claim is:

1. In an electrical ignition device, the combination of a magneto, a driving shaft, a train of gears connecting said driving shaft

and magneto, and means for varying the angular relation of the magneto shaft to the driving shaft to vary the time of delivery of the spark, said means comprising a 5 gear mounted on the magneto shaft so as to be capable of angular movement relatively thereto, a cap equipped with a cam slidable longitudinally of the shaft, said cam being constructed to engage with said gear to cause 10 an angular movement of the gear, and a cam movable transversely of the shaft for actuating said cap.

2. In an electrical ignition device, the combination of a magneto, a bearing sector 15 secured to the magneto shaft, a driving gear carried by said sector capable of limited angular movement thereon, a tapered cam movable longitudinally of the shaft to engage with said gear and adjust the gear 20 angularly on said shaft, and means for actuating said tapered cam.

3. In an electrical ignition apparatus, the combination of a magneto, a perforated plate provided with a bearing sector secured 25 to the magneto shaft, an annular gear having an inwardly projecting lug carried by said sector, and a tapered cam adapted to be inserted between said lug and the side wall of the perforation in said plate for adjusting 30 said gear angularly on the bearing sector, and means for actuating said cam.

4. In an electrical ignition apparatus, the combination of a magneto, a perforated plate secured on the shaft and provided with 35 a bearing sector, a gear mounted on said sector so as to be capable of limited angular movement relatively thereto, a cap loosely mounted upon the end of said shaft and having a tapered cam adapted to adjust said 40 gear angularly, a housing disposed over said cap, and a cam mounted in said housing to move transversely of the magneto shaft to actuate said cap.

5. In an electrical ignition device, the combination of a magneto, a plate secured 45 upon the magneto shaft, an annular gear carried by said plate and capable of limited angular movement on the plate, a cam member adapted to be moved longitudinally of

the magneto shaft to engage with said plate 50 and gear and vary their relative angular position, and means for actuating said cam member, comprising a manually operable cam adapted to be moved in a direction at right-angles to the movement of the cam 55 member.

6. In an electrical ignition apparatus, the combination of a magneto, a plate secured to the magneto shaft and provided with a perforation and an annular track, a gear 60 carried by said plate capable of limited turning movement relatively to the plate, a cam member movable longitudinally of the magneto shaft into the perforation in said plate to engage with said gear and impart 65 rotary movement thereto, and manually controlled means for actuating said cam member.

7. In an electrical ignition apparatus, the combination of a magneto shaft, a perforated disk secured on said shaft, a ring provided with a bearing sector fastened to one face of said disk, an annular gear carried by said bearing sector between the ring and said disk, said gear being provided with an 70 inwardly projecting lug, and a cam adapted to engage said lug and enter the perforation in said disk to adjust the gear angularly 75 relatively to said shaft.

8. In an electrical ignition apparatus, the combination of a magneto shaft, a perforated disk secured thereon, an annular gear loosely mounted on said disk so as to be capable of angular adjustment relatively thereto, and provided with an internally arranged lug, a set-nut threaded upon the end of the shaft, a cap adapted to slide longitudinally of said set-nut, said cap being provided with a cam adapted upon longitudinal movement of the cap to engage the lug 80 on said gear and adjust the gear on the disk, and means for engaging said cap to impart 85 longitudinal movement thereto.
